UNITED STATES PATENT OFFICE.

WILFRED A. BROTHERTON, OF ROCHESTER, MICHIGAN.

POCKET-CUSPIDOR.

1,072,695.

Specification of Letters Patent.

Patented Sept. 9, 1913.

Application filed November 5, 1912. Serial No. 729,681.

To all whom it may concern:

Be it known that I, WILFRED A. BROTHERTON, a citizen of the United States, residing at Rochester, in the county of Oakland, 5 State of Michigan, have invented certain new and useful Improvements in Pocket-Cuspidors; and I do hereby declare the following to be a full, clear, and exact description of the invention, such as will enable others skilled in the art to which it 10 appertains to make and use the same.

This invention relates to pocket cuspidors and has for an object to provide a compact flexible device of this character 15 that will retain fresh sputa and positively destroy disease germs therein.

To meet this urgent demand I have provided a compact inexpensive and positively 20 bacteria destroying pocket cuspidor which will be hereinafter fully described and claimed, it being understood that various modifications may be resorted to within the scope of the appended claim.

In the accompanying drawing forming 25 part of this specification:—Figure 1 is a side elevation of the device. Fig. 2 is a longitudinal sectional view through the device. Fig. 3 is a cross sectional view taken on the line 3—3 Fig. 1.

Referring now to the drawing in which like characters of reference designate similar parts, 10 designates a sack of the general shape shown and formed of strong 30 flexible waterproof paper or other material. The sack is lined with a thin layer of absorbent cotton 11 or other absorbent material, this lining element being charged with a suitable disinfectant sufficiently powerful 35 to immediately destroy all pathogenetic bacteria. This lining element is thickest at the bottom of the sack as shown.

In the bottom of the sack upon the lining element is placed a powerful bactericide 12 in powdered form, this bactericide being loosely covered with absorbent cotton 45 13 or other absorbent material saturated with powerful disinfectant. The complete lining above described will absorb all sputa expectorated into it and immediately destroy the disease producing bacteria in the 50 sputa.

A funnel-shaped mouthpiece 14 is cemented, glued or otherwise rigidly secured in the throat of the sack, this mouthpiece being formed preferably of soft, absorbent 55 paper, and is placed about the lips in expectorating, and furthermore may be utilized in wiping the lips after expectorating, being then inserted bodily into the sack.

A pliable collar 15 is secured exteriorly 60 to the mouth of the sack and is preferably formed of tinfoil or the like, this collar being designed to close the mouth of the sack by folding upon itself or being rolled upon itself after the mouth piece has been 65 thrust inside of the sack. The article may be now burned or otherwise destroyed.

What is claimed, is:—

The combination with a flexible sack and a flexible mouth-piece in the throat of said 70 sack, of a metallic pliable collar exteriorly encircling the mouth of said sack and normally holding open said sack, said collar being adapted to be rolled or folded upon 75 itself to seal the mouth of said sack after insertion of said mouth-piece into said sack.

In testimony whereof, I affix my signature, in presence of two witnesses.

WILFRED A. BROTHERTON.

Witnesses:

EDWARD H. ROGERS,
GEORGE A. MARGETTS.
